DESIGN FOR A SANDAL OR SIMILAR ARTICLE

Howard A. Jarvis, Los Angeles, Calif.

Application November 25, 1941, Serial No. 104,320

Term of patent 14 years

To all whom it may concern:

Be it known that I, Howard A. Jarvis, a citizen of the United States, residing at Los Angeles, in the county of Los Angeles and State of California, have invented a new, original, and ornamental Design for a Sandal or Similar Article, of which the following is a specification, reference being had to the drawing forming part thereof.

I claim:

The ornamental design for a sandal or similar article, substantially as shown.

HOWARD A. JARVIS.
